UNITED STATES PATENT OFFICE.

ROSWELL A. MOORE, OF WATERBURY, CONNECTICUT, ASSIGNOR TO WATERBURY BUCKLE CO., OF WATERBURY, CONNECTICUT, A CORPORATION.

GARTER TRIMMING.

Application filed October 22, 1921. Serial No. 509,662.

To all whom it may concern:

Be it known that I, Roswell A. Moore, a citizen of the United States, residing at Waterbury, in the county of New Haven and 5 State of Connecticut, have invented a new and useful Improvement in Garter Trimmings; and I do hereby declare the following, when taken in connection with the accompanying drawings and the characters of 10 reference marked thereon, to be a full, clear, and exact description of the same, and which said drawings constitute part of this application and represent in.

Fig. 1 A view in elevation of a garter 15 embodying my invention.

Fig. 2 An enlarged view in transverse section on the line 2—2 of Fig. 1.

Fig. 3 A detached perspective view of the cast-off plate.

20 Fig. 4 A similar view of the cast-off washer.

Fig. 5 A view in elevation of the cast-off stud.

My invention relates to an improvement 25 in garter-trimmings of that class in which the cast-off plate is offset from one edge of the pad, instead of being imposed thereupon, as is the common practice, the object of my present invention being to produce 30 a cheap and comfortable article constructed with particular reference to minimizing the amount of metal exposed in connection with mounting the cast-off stud.

With these ends in view, my invention 35 consists in a garter-trimming having certain details of construction as will be herein-after described and particularly pointed out in the claim.

In carrying out my invention, as herein 40 shown, I employ a one-piece, sheet-metal cast-off plate 10 having openings 11 separated by a central transverse bar 12 formed with a perforation 13 located on the inside of the major axis of the plate, which is enough 45 shorter than the width of the webbing used to form the loop 14 to permit the edges of the webbing to be stitched at 15, so as to completely enclose the plate if desired, though I would have it understood that 50 this stitching is not necessary to the successful practice of my invention. The webbing used for the loop 14 will, by preference,

correspond to the webbing used in the leg-band 16, which has its inner end fastened to the pad 17 and its free outer end provided with a cast-off eye 18 and a slide 19, by means of which latter the length of the leg-band 16 is adjusted, as may be desired. The pad 17 is provided with any standard 55 hose-gripping pendant 20.

The webbing of the loop 14 is folded upon itself so as to completely enclose the cast-off plate 10, as shown in Fig. 2, the ends of the webbing being inserted between the face pieces of the pad 17 and stitched in 60 place as at 21. The said plate forms a core 65 for the loop, which it extends and maintains in flattened form and prevents from buckling or collapsing. Prior to stitching the ends of the loop 14 into the pad 17, the cast-off washer 23 having been applied to the reduced end of the stud 22, the same is passed downward through the upper reach 70 of the webbing and through the perforation 13 in the plate 10 upon the lower face 75 of which the projecting end of the rivet is headed, as at 25, whereby the upper reach of the webbing is pinched between the upper face of the plate 10 and the lower face of the washer 23, and whereby the head 25 of the rivet 22 is entirely covered and protected 80 by the lower reach 26 of the webbing. By locating the perforation 13 in the plate 10 nearer the inner than the outer edge of the same, and therefore accordingly locating the cast-off stud in the finished article, I provide 85 a bearing for the cast-off eye 18, which is thus prevented from coming in contact with the leg.

It will thus be seen that, by a very simple 90 and cheap construction, the cast-off plate is located entirely out of sight and protected. This avoids the necessity of finishing the plate and adds to the attractiveness of the garter, since it is desirable to reduce the 95 amount of exposed metal to the minimum in high-class goods of the class to which this invention belongs.

I claim:

In a garter-trimming, the combination 100 with a loop of webbing, of an oblong-shaper plate corresponding in length to the width of the webbing composing the said loop and corresponding in width to the length of the

loop within which the said plate is located to maintain it in flattened form and prevent it from collapsing, a washer imposed upon the upper reach of the said loop, a shouldered cast-off stud carrying the said washer and passed downward through the upper reach of the said loop and through the per-

foration in the said shaper plate and headed down upon the lower face thereof and covered by the lower reach of the said loop; and a cast-off eye for co-action with the said cast-off stud.

ROSWELL A. MOORE.
